UNITED STATES PATENT OFFICE.

JOHAN HILDING HEDBERG, OF HELSINGBORG, SWEDEN.

BLOTTING APPLIANCE.

1,345,087.

Specification of Letters Patent. Patented June 29, 1920.

Application filed August 9, 1919. Serial No. 316,514.

To all whom it may concern:

Be it known that I, JOHAN HILDING HEDBERG, a subject of the King of Sweden, residing at Helsingborg, Sweden, have invented certain Improvements in Blotting Appliances, of which the following is a specification.

When signatures are written successively in large numbers, a great deal of time is wasted in the employment of the usual blotting-appliances such as a loose blotting-paper or pad which is easily mislaid and has to be looked for. Even if, as has been proposed, a blotting roller or pad is connected to the tail end of a pen-holder so that it can be applied by means of the latter to the writing, the writer has for this purpose to change his grip on the pen-holder, which means trouble and waste of time.

The object of the present invention is to produce a blotting-appliance which, being connected to the pen-holder, can be instantly applied by a mere turn of the pen with the hand without the grip on the pen-holder being altered, and consists in the combination with a small flat blotting paper support held by a projecting neck at or near a corner of the blotting paper support so that, attached to the nib end of the pen-holder, it will hold the blotter away from the holder in a leftwardly and rearwardly projecting position. In such position the blotter will, without obstructing the pen or interfering with the free use thereof, be ready for immediate and convenient application to the writing as above described.

In the accompanying drawings the invention is illustrated by way of example,

Figure 1 showing the position of the pen and blotting-appliance while the writing is in progress, and

Fig. 2, the position of the same when the writing is blotted.

Fig. 3 is a view of the blotting-appliance by itself and in the same position as in Fig. 2.

Fig. 4 is an elevation of the appliance, and

Fig. 5, a cross-section on the line $a-a$ of Fig. 4.

Fig. 6 is a plan of a modified construction, and

Fig. 7, an elevation of the same.

A blotting-paper support in the form of a small flat plate 2 is provided or formed with means whereby one or several superposed sheets of blotting-paper can be held against its bottom surface. It has also, projecting by means of a neck from its top surface, a clip 1 by means of which the device can be attached to a pen-holder, near the nib, in about the manner shown in Fig. 1, with the blotter projecting leftwardly and rearwardly in the gap formed by the thumb and the forefinger. It is adjusted in such a position as not to interfere with the free use of the pen and so that by a mere turn of the hand and the pen-holder, the blotting-paper will be in a position for application to the writing, as shown in Fig. 2.

For holding the blotting papers spring clips 3 may be employed, the ends of the blotting-paper sheets being folded over opposite edges of the plate 2 and tucked under the springs as shown in Figs. 3 and 4. The plate 2 and the clips 1 and 3 may be stamped out of the same metal plate and thus formed integrally with each other. Suitable pads may be made up of several superposed sheets of blotting-paper with a support of ordinary thick paper, the ends to be fastened to the holder 2 being stuck together by glue applied to the assembled edges. One of the free edges of the pad 5 is preferably beveled off, as shown at 4 in Fig. 5, so as to facilitate the removal of the single blotting-paper sheets as they become useless.

If loose sheets are employed, the plate 2 is preferably lined with cloth, card-board or other suitable material.

An alternative arrangement for fastening the blotting-papers is shown in Figs. 6 and 7 according to which the blotting-papers are held by the over-turned edges of the plate support 2'. Moreover, the clip 1, instead of being made integrally with the plate 2', is attached to the top surface of the same.

The actual position of the blotting-appliance on the penholder may be varied accord-

ing to taste and convenience. The shape of the clip 1 may be varied to suit different kinds of pen-holders.

I claim:

- 5 A blotting appliance comprising the combination with a small flat blotting paper support of a clip held by a projecting neck at or near a corner of said support so that, attached to the nib end of a pen-holder, it

will hold the blotter away from the pen- 10 holder in a leftwardly and rearwardly projecting position, substantially as described and illustrated.

JOHAN HILDING HEDBERG.
